UNITED STATES PATENT OFFICE.

ELVIN V. HUCKELBERRY, OF ERIE, PENNSYLVANIA.

COMPOSITION-ROOF-LAYER MACHINE.

1,324,050.

Specification of Letters Patent.

Patented Dec. 9, 1919.

Application filed December 18, 1918. Serial No. 267,301.

To all whom it may concern:

Be it known that I, ELVIN V. HUCKELBERRY, a citizen of the United States, residing at Erie, in the county of Erie and State 5 of Pennsylvania, have invented certain new and useful Improvements in Composition-Roof-Layer Machines; and I do hereby declare the following to be a full, clear, and exact description of the invention, such as 10 will enable others skilled in the art to which it appertains to make and use the same, reference being had to the accompanying drawings, and to the letters of reference marked thereon, forming part of this specification. 15

My invention relates to laying composition roofing composed of alternate layers of tar impregnated paper and asphaltic pitch, and consists in providing an apparatus by 20 means of which liquefied asphalt, tar or pitch can be applied to the surface to be covered, and a layer of paper or other fabric laid thereon and rolled down.

In carrying out my invention I construct 25 a vehicle adapted to carry a container for the liquefied tar from which a pipe leads to a distributing pipe provided with perforations from which the tar will drop on to the surface to be covered; and on the vehicle is 30 secured a roll of suitable roofing material, such as tar saturated paper, the end of which passes under a weighted roller, the function of which is to press the paper down upon the layer of tar distributed by 35 the distributor, so that as the vehicle is moved over the surface to be covered the tar and paper are properly spread thereon.

The features of my invention are fully 40 set forth hereinafter, and are illustrated in the accompanying drawings in which:—

Figure 1, is a side elevation of my roofing apparatus.

Fig. 2, is a plan view of the same.

In these drawings A indicates the frame, 45 and A' A' indicates the supporting wheels of my roofing apparatus.

The frame A is provided with cross-bars a—a on which is placed a tank B in which I place a supply of liquid tar. From the 50 bottom of the tank B a pipe B' (see Fig. 1) leads to a horizontal distributing pipe b which extends transversely across the apparatus adjacent to the surface to be covered. The pipe B' is provided with a shut-off valve b', which has a valve-stem b², and a lever b³ for operating the valve. Adjacent to the rear side of the horizontal distributing pipe b is a weighted roller C the axle of which is mounted in bars C' C' at each end of the roller, one end of each of 60 said bars C' C' being pivoted to the rackets D D secured to the frame A, and the other ends of the bars C' C' are pivoted to a bifurcated lifting bar D', which is provided with a hook d so that when it is desired to 65 elevate the roller C the hook d may be raised upward and hooked on the frame A as indicated in broken lines in Fig. 1.

Mounted in suitable bearings on the frame A beside the tank B is a rod E upon 70 which I place a roll of tar paper F; and the end f of the paper is passed around and under the roller C which presses it down upon the surface G to be covered. Tar is permitted to flow to the perforated distributing pipe b and escape therefrom to the surface G, and as the vehicle is drawn forward lays a thin coating of tar thereon, and the paper f unrolls and is pressed down upon the tar by the roller C. When the 80 end of the course is reached the valve b' is closed, the roller C elevated, the paper cut off, and the apparatus turned around ready for the next course.

Having thus described my invention and 85 suitable means for embodying it, I do not desire to be limited to the exact construction thereof herein shown and described, but what I claim as new and desire to secure by Letters-Patent is:

1. In an apparatus of the class described, a vehicle, a liquid cement container thereon, means connected therewith to distribute a layer of the cement upon a surface over which said vehicle is drawn, a vertically 95 movable roller in said apparatus adapted to press a continuous strip of material upon said layer of liquid cement, as the same is distributed, and means to manually raise and lower said roller, substantially as described.

2. In an apparatus of the class described, a vehicle, a tank thereon, a pipe projecting downwardly from said tank, a perforated transverse pipe connected to the lower end of said first mentioned pipe, a weighted vertically movable roller mounted in said apparatus behind said transverse pipe, means to manually raise and lower said roller, and means to support a roll of roofing material on said vehicle so that the free end thereof will pass over and under said ver-

tically movable roller, substantially as set forth.

3. In an apparatus of the class described, a vehicle adapted to be moved over a surface to be covered with roofing material, a liquid cement container, a cement distributor connected with said container, a weighted roller behind said distributor, brackets secured to said vehicle, bars pivoted to said brackets 5 and extending therefrom past the ends of said roller adapted to receive the journals

of said roller; means pivoted to the free ends of said bars adapted to guide said bars laterally and raise and lower them when desired, and means to support a continuous 15 sheet of roofing material on said vehicle so that the free end thereof may pass between said distributor and said roller, and between said roller and the surface to be covered, substantially as set forth. 20

In testimony whereof I affix my signature.

ELVIN V. HUCKELBERY,
